UNITED STATES PATENT OFFICE.

NATHANIEL G. WARTH, OF COLUMBUS, OHIO.

TELEPHONE-REPEATER.

960,458.

Specification of Letters Patent. Patented June 7, 1910.

Application filed December 14, 1908. Serial No. 467,328.

To all whom it may concern:

Be it known that I, NATHANIEL G. WARTH, a citizen of the United States, residing at Columbus, in the county of Franklin and State of Ohio, have invented a certain new and useful Improvement in Telephone-Repeaters, of which the following is a specification.

The object of this invention is to provide means whereby a telephone repeated current is more nearly assimilated as to form to the initial or transmitting current, and amplified in its volume so that speech or other sound is reproduced at a distant station with greater force and clearness than has heretofore been realized.

The invention consists in the matters hereinafter described and pointed out in the claims.

Telephonic currents being small at best, owing to the very weak or exhausted character of the currents usually available in one direction, and frequently in both directions, at a repeater station, it has been required, in order to secure such results as have heretofore been attained, to make the mobile parts of repeaters, such as armatures, diaphragms and electrodes, very small and of light weight, so that they should be capable of operation by ordinary speech or vocal currents. The superior efficiency and strong transmitting quality of the well known Hunnings or granular type of transmitting instrument for ordinary telephone service has caused it to be adapted, in the form of the also well known White "solid-back", button transmitter, as the best known instrument for repeating and reinforcing telephonic transmission. I have found that this instrument, even when constructed in the most delicate and perfect manner for such service, and when used with a highly efficient receiver, has such mechanical resistance to actuation by the weak currents in the receiver that the repeated currents are distorted in form, or character; that some waves are lost, between the receiving element and the transmitting element, not being reproduced when received, and that the amplitude of vibration is restricted, correspondingly restricting the volume and power in reproduction, and decreasing the range of transmission. The resistance to actuation offered by the aforesaid form of transmitter is due mainly to the stressed and peripherally clamped and bounded dia-

phragm of the carbon button, and the trouble is aggravated by the added stress of the diaphragm due to the pull of the sensitizing magnet, which causes the diaphragm to reach practically its limit of movement in one, usually the forward, direction. This resistance to motion is further increased by the inertia of the relatively heavy mass of matter carried by the diaphragm, embodying the vibratory armature and electrode, together with their means of attachment to the diaphragm. Were the operating currents of sufficient strength to actuate this mechanism, reduced as it is to its practicable minimums of weight, and size, and increased to its maximum of practicable mobility, the transmitter would render very much improved results, both as to the quality and as to the volume of the reproduced currents.

By means of my present invention I am enabled to accomplish the results sought in a highly practical and efficient manner. This I do mainly by the use of a double relay or repeater, one acting as an auxiliary to the other, adapting each to its particular functions, and although somewhat complicating the repeater mechanism and operation, yet justifying this step by the improved results and with their small additional cost. I employ the receiving element of the granular carbon transmitting repeater in a local repeating circuit, and utilize the repeater in a secondary capacity as a "transmitting" repeater or as the "transmitter" of the double arrangement. In this arrangement the secondary repeater is operated by its receiver element, or on its receiver side, by the reinforced current, from a "main line" repeater, thus utilizing a very efficient "receiving" repeater provided with a very sensitive transmitter. The combination operates as follows: the sensitive "receiving" repeater, faithfully reproduces the telephonic waves received from the transmitting end of the line and transfers them by means of a local circuit arrangement to the more powerful "transmitting" repeater for reproduction and retransmission with reinforced power to the terminating or receiving end of the line. The receiver in such cases, operating imperfectly and only with the power of the attenuated line currents, cannot produce a sufficiently vigorous actuation of the transmitter to secure clear and strong retransmission, while with my method the heavy service transmitter is actuated by a

comparatively strong local current, which current is very nearly a perfect fac-simile of the original current, and the resultant reinforced line current is very similar in form and in strength to the original transmission.

The results obtained from the use of the telephone repeater indicate that serious attenuation of the currents in the line occurs before serious distortion, and this condition works to advantage for long distance transmission by means of the repeater. Were it possible to eliminate the difficulty of attenuated line currents the use of a repeater would be unnecessary, but as the use of a repeater appears the best solution of extraordinarily long-distance transmission, and the cheapest solution of ordinary long-distance transmission, it will be a great gain if the telephone repeater be made as efficient and as satisfactory in telephony as the telegraph repeater is in telegraphy. As further means to this end, I employ in the receiving element of each repeater, a polarized armature influenced by both the attractive and repulsive effects due to the alternations of the telephonic current in the receiving magnets or windings of the "receiving" and the "auxiliary" relays for the purpose of increasing the efficiency of said receiving elements.

I will now proceed to describe a particular exemplification of my invention in connection with an illustration of the same in the accompanying drawings.

In said drawings—Figure 1 is an illustration in side elevation, partly in section, of the repeater for receiving the weak inward currents from the line, and for reproducing and reinforcing them for the auxiliary or transmitting local repeater to re-repeat with re-reinforced current and effect to the outward line. Fig. 2 is an illustration of my secondary or transmitting repeater, used for reinforcing the reinforced, quality maintained currents from the receiving line-repeater. Fig. 3 is a diagrammatical illustration of my double repeater, showing the arrangement of apparatus and circuits for repeating in but one direction, that is, it represents but one side, or half, of a reciprocal repeater of this invention. Fig. 4 is a diagrammatical illustration of my double repeater adapted to, or as used with, the form or type of twin repeater, shown in my patent of the United States No. 894,170, of July 21st, 1908, and a modified arrangement in my pending application filed July 15th, 1907, S. No. 383,883. This arrangement of the apparatus and circuits provides for reciprocal repeating, showing both halves of a reciprocal repeater under the present invention and forming a twin double repeater giving unidirectional retransmission.

In Fig. 1 the character B designates a base of insulating material, circular in form,

supporting the delicate receiving repeater R and the glass covering G for same. U designates the sensitizing permanent magnet for creating an initial magnetic field for the receiving coil C and for polarizing the spring supported iron armature A. The magnet U is, by means of brass screws b, b, mounted upon the brass bracket D. A soft iron tube t driven, or screwed, into a perforation in the south or S pole of the permanent magnet, and also passing through a corresponding perforation in the brass bracket D, forms the core for the receiving coil C. An adjustable extension for this core is provided in the screw bolt t¹, which, by means of its exterior threads and the interior threads in the core tube t, is rendered adjustable toward or away from the polarized armature A. The end of this screw bolt t¹ is furnished with a very small copper tip P to prevent the polarized armature A from sticking to it if it should contact therewith. The coil C is placed upon the polar end of the tube t to cause it to vary the magnetic flux with its maximum effect. The opposite pole N, or north end, of the permanent magnet U is equipped with means for supporting, and for regulating the adjustment of the sensitive transmitter, said transmitter embracing the platinum electrode e and the carbon button electrode c. The platinum electrode e and the armature A are fixed upon the lower end of the light spring or steel tongue a, which is carried and insulated by the support d between the bracket D and the N pole of the magnet U. This support is formed by three insulating blocks, as shown, bridging the space between the bracket and the magnet, and is held in place by a screw or screws f passed through proper screw holes in the bracket and magnet, and also extending through the insulating blocks out of connection with the springs a and a¹. The spring or tongue a¹ carries the carbon button electrode c, the button being fastened to it by means of a small machine screw g, that can be manipulated by a screw-driver through the orifice h in the bracket D. The button c is similar to, but smaller than, the old well known Blake transmitter button, and comprises a hard carbon member for contact with the opposing electrode mounted upon a brass back, said member being provided with a threaded hole for the fastening screw g. The tongue a¹ is elastic and can be adjusted by means of its own tension and the set screw i passed through and supported by the bracket D. This adjusting screw i is provided with an insulating tip to prevent electrical contact or connection with the steel tongue a¹, to avoid short circuiting the transmitter through the bracket D and magnet U with the platinum electrode tongue a. An adjusting screw of iron j passed through the N pole of the

magnet U serves in the adjustment of the tongue *a* to provide a path for the magnetic flux to more easily reach the steel tongue and through it the armature A to polarize the latter. An iron contact disk *k* attached to the tongue *a* at the point of contact with the iron screw *j* serves to improve the path of the magnetic flux to the armature.

The adjustment of the parts should be such that the iron contact disk constantly bears upon the point of the screw *j*. This contact is aided by the attractive effect of the pole of the magnet for the disk *k* and tongue *a*. The armature A should be held close to, but out of contact with, the extension core *t*. The tongue *a*¹ should be adjusted to lightly follow the vibrating platinum electrode, so as always to remain in contact therewith. It will be noted that the inertia of the tongue *a* plus the combined weight of the small armature and platinum contact is very small, and that the pushing tendency of the carbon electrode even reduces it, hence it is very responsive to weak telephonic currents. The battery flow between the electrodes can be very small because the work to be done in repeating to the transmitting repeater through the local circuits is light; and further very little heat is developed in the transmitter. The two steel tongues serve to lead the battery current to and from the electrodes, and connections are made with them for the purpose by means of the wires L L¹ leading from the binding posts M, M¹. The light vibratory tongues, *a* and *a*¹ the latter dominating the former to damp its movement while highly sensitive and responsive to the magnetic influence set up by coil C are not of the character of free vibrating tongues or reeds, as they are, by reason of their limited length, their supports, adjustments, and their continuously opposed spring tension between the electrodes, prevented from undergoing or setting up vibrations of their own. In short they are "damped" and under constant control of the magnet, or coil C, and incapable of performing fundamental periodic, or so called "harmonic" vibrations. Such vibrations, if permitted, would be fatal to correct reproduction of telephonic voice currents.

A large machine screw E of iron passes through the screw hole F to serve as a shunt for the magnetic flux and reduce the magnetic attraction on the armature A when such attraction is in excess of that needed to set up a properly proportioned initial field for the electro-magnet and sensitize the armature. This regulation is secured by moving the point of the screw E toward the head of the iron screw *j* until the initial pull upon the armature A is reduced to an amount which permits the electro-magnetic variations to act with a maximum value

upon the armature. The action of the polarized armature A is to increase the effects of the usual attraction and withdrawal of the armature by the electro-magnet. The magnetic circuit is improved by said arrangement because the magnetic flux path aforesaid is almost closed, the only gap being that between the end of the pole marked *s* and the armature, marked *n*. These polar extremities are extensions of the south and north poles respectively of the permanent magnet U and have a normal mutual attraction in proportion to the density of the magnetic flux. A current in the electro-magnet coil C, if of a sign to reinforce the permanent flux, will produce a forward movement of the armature A, said movement being augmented by the mutual attraction of the polar extremities, and by the released forward tension of the tongue *a*¹. The forward movement of the electrode *c* and its momentum due to its inertia will aid in varying the resistance at the point or points of contact between the platinum and carbon electrodes. A current in the coil C if of a sign opposing the permanent flux, will, if the permanent flux is properly proportioned, cause not only a weakening of the normal attraction, but an additional effect of repulsion between the polar extensions *s* and *n*, resulting in an opposite movement of the armature, which is an augmented effect or increase, of the usual retraction. The platinum front electrode *e* is preferred in this instrument to one of carbon, because it can be of small size and weight, and in some instances of use both electrodes should be of platinum or other suitable metal. The receiving coil C is associated with the circuit by means of the binding posts V V¹.

In Fig. 2, which illustrates the secondary or transmitting instrument for the heavy current work, the base B¹ is of insulating material and carries the repeater instrument which is covered by the glass cover or case G¹. The electro-magnetic receiving coil C¹, and its polar extremities K, K¹, are supported by brackets D², D³, and the terminals of the coil are connected with the screw binding posts V² V³. This coil should be wound with fairly coarse magnet wire if placed in the primary circuit, with the transmitter and battery of the receiving repeater. If said coil is used in a circuit secondary to such primary circuit, with an induction coil interposed between them, the winding should be of smaller magnet wire and be in accordance with the secondary winding of the induction coil. I prefer to separate the local circuit connecting the primary and secondary repeaters, as indicated above, and illustrated in Fig. 3, as the strong polarizing effect of the battery is then avoided in the secondary repeater. As illustrated in Fig. 2 this repeater has no permanent magnet, or

coil, for polarizing or creating an initial field for sensitization. The sensitization utilized is the magnet flux of the polarized armature A^2 , set up by the permanent magnet U^2 , and the magnetic flux is conducted from the N^2 pole of the magnet U^2 to the armature by the small flexible steel tongue a^2 , which is secured to the pole of the magnet and to the armature in a suitable slot in each. The armature is prevented from making contact with or sticking to the polar extremities K^1 K^4 of the electro-magnet C^1 , by small copper points P^1 P^2 embedded in the pole surfaces. The magnet U^2 is supported and kept in place upon the base B^1 by having its south pole S^2 fastened thereto. The action of the polarized armature A^2 under the influence of the electro-magnet resembles the action described in connection with the receiving repeater in Fig. 1. In this case of the construction of Fig. 2 there is no effect to be considered in connection with a permanent magnet for initially magnetizing the poles of the electro-magnet. Said instrument may be constructed with such a magnet, but I prefer the electro-magnet which is here illustrated, as it better avoids undue stress upon the mica transmitter diaphragm a^3 , and leaves the latter in a more sensitive state. The armature, instead of being mounted upon, or directly connected with, the transmitter diaphragm a^3 , as is usual, is, because of its distance from the armature, connected with said diaphragm mechanically by means of the slender and light arm a^4 . Said arm a^4 is attached to the armature by screw threads and also to the diaphragm. The front electrode button e^3 is fastened in electrical connection to its metal back e^1 placed upon the rear of the diaphragm. A nut e^2 is placed upon the front of the diaphragm and the arm a^4 is screwed through them, the nut e^2 serving, when set tightly, to hold the parts firmly to the diaphragm. The transmitter T is mounted, by means of the screws b^2 b^3 , upon the bracket or pedestal D^1 , which may be slideable upon the base B^4 and fastened to same by the screw d^2 . The rear electrode e^2 of carbon is electrically connected to the rear wall of the granular carbon-containing chamber c^1 . The diaphragm is tightly clamped to the transmitter casing by the threaded ring f^2 , and the annular space between the electrodes is nearly filled with carbon granules. The front electrode e^3 is connected by a small copper wire with the binding post M^2 , and the connection to the rear electrode is through the bracket support D^1 to the binding post M^3 .

The alternating telephonic currents cause the polarity of the electro-magnet to correspondingly change, and the alternating polar effects in the poles marked s^2 and n^2 cause the polarized armature A^2 to oscillate or

move between the poles in practical synchronism therewith. Each movement of the armature, to or fro, effects the resistance of the granular carbon transmitter correspondingly by the impressed motion upon its diaphragm through the connecting arm a^4 , in the usual manner. The particular advantage of this polarized armature arrangement lies in the improved control of the armature by the attraction and repulsion effects thereon. The armature and its connecting arm to the transmitter are elastically supported by the steel tongue a^2 , and the initial stress upon the diaphragm is that due to the mild attraction of the polarized armature to the pole of opposite sign. The transmitter is thus in a very sensitive state and responds easily and effectually. A telephonic impulse acting through the electro-magnet to increase the attraction of the armature toward the pole it normally seeks—the pole of opposite sign,—also creates a repulsive effect between the armature and the other pole, thereby augmenting the action. This arrangement results in a greater movement than were the diaphragm under considerable stress by a permanent magnet, as is usual in the ordinary magneto-electric receivers and similar receivers in repeaters; hence, the transmitter receives a correspondingly increased vibration. A telephonic impulse of the opposite sign produces an increased effect by a corresponding co-operation between the magnets, in the opposite direction. That is, the actions are the same but opposite in effect, and said increased effect is owing to the tendency of the diaphragm to resume its normal position when relieved of the initial stress.

Fig. 3 diagrammatically illustrates the arrangement of the apparatus and its sequence of operations from the reception of a telephonic impulse from the incoming line to its retransmission to the outgoing line, after having been twice reproduced and "stepped up" in volume. The primary or receiving repeater in this view comprises the receiver, transmitter, battery, induction coil, and circuit connections to the left of the dotted line. The secondary or transmitting repeater comprises the corresponding apparatus and circuits to the right of the dotted line. The incoming line circuit L^2 and outgoing line circuit L^3 , terminals shown represent the connections respectively to the inductive local repeater circuit and the main line circuit shown more fully in Fig. 4. The operations involved in transmitting in one direction with this half or one side of the repeater arrangement is as follows: Weak telephonic impulses from line L^2 actuate the first receiving repeater R , which reproduces the impulses, and, as before stated, with increased power, through the primary local circuit P^2 inductively by means of the in-

duction coil I into the secondary local circuit LC where the impulses actuate the transmitting repeater R², which, due to the strength of the currents from the line repeater, is enabled to re-repeat the original impulses with much greater power and accuracy than would a repeater operated directly by the original impulses and adapted to actuate a high power or granular transmitter varying a strong local battery, as has heretofore been the practice. The repeated currents from repeater R² and its primary local circuit P⁴ are directly induced through the line induction coil I² into the outgoing line L³, whence they are transmitted toward the terminating station.

In Fig. 4 is illustrated the method of utilizing my double repeater apparatus to secure repeater service both ways, or reciprocally, over a repeater line circuit. In this arrangement two double repeaters are necessary in order to secure unidirectional reciprocal retransmission. The arrangement shown is a combination of the present invention with my patented circuit system hereinbefore referred to, in which retransmission is secured with no interference due to reaction effects in the apparatus or system, and full transmitting efficiency is had in each direction from each repeating transmitter.

The designating marks R and R² for the receiving repeater and the transmitting repeater respectively, shown in Fig. 3, will serve to identify them in this view as the repeaters operating to repeat from line L² to line L³, as explained. The arrows indicate the current flows in both the local and secondary circuits and accord with the effects set up when a given or single impulse is received from line L³, and which is repeated into line L². Tracing the circuit, the current flows are as follows: from line L³, line wire W³, to the left and through the secondary winding of line induction coil I² to line wire W⁴. These flows set up currents in the receiver local circuit B³, the resulting current flow corresponding to the arrows to energize repeater receiver R³. The similarly set up currents in the primary circuit P⁵ coöperate through the auxiliary induction coil C³ to energize the receiver. The actuation of the repeater R³ induces currents from its primary local circuit P⁴ through induction coil I³ into the secondary local circuit LC², resulting in the actuation of the secondary repeater R⁴. This latter repeater causes the local battery LB² in primary circuit P⁶ to induce strong currents into line L² through the line induction coil I⁴. The flow of the current in the primary circuit, as shown by the arrows, induces a current in the line which flows inward in wire W and outward in wire W². The current in primary circuit P⁶ also induces a

current in the local circuit B² of repeater R, which would energize and actuate that repeater and cause it to react and become noisy, were it not that the induced current in auxiliary induction coil C² from the same primary circuit is made to balance and oppose the other current in local circuit B², as will be understood from the arrows associated with that circuit. As to the receiving side, it will be remembered that the local current flows in local circuit B³ co-operated to energize the repeater, while in this case, on the transmitting side they are in opposition to prevent energizing the repeater R. The cycle of operations is reversed in the apparatus when the transmission is from the line L² to the line L³.

This application for patent shows and describes but one general form of my invention, but it is obvious that those skilled in the art to which it appertains will be enabled to vary or change the details of the circuits and the apparatus without departure from the spirit and scope of the invention.

I am aware that attempts have been made to secure retransmission of reinforced telephone currents by the use of a pair of relays, one serving in a secondary capacity to the other, but so far as I am aware, such attempts have not been successful and have not gone into practical or commercial operation. The prime requisites of a repeater of this character is a primary relay device nicely proportioned to the weak currents that are available for its operation, correspondingly proportioned members in the secondary relay device for its available currents, a properly proportioned battery supply for each, and an adjustment in the transmitter for each, which permits the normal microphonic effect, and avoids undue pressures or distortions in the resulting currents at any stage of the operation.

What I claim as new and desire to secure by Letters Patent, is—

1. The combination in a telephone repeater, of two repeaters, each including a pair, at each repeater station, each pair adapted to repeat in a direction opposite to the other, each pair comprising a compound telephone repeater composed of a receiving or primary-relay and a transmitting or secondary-relay; the primary relays consisting of a sensitive receiving telephone and transmitting microphone without a diaphragm, and a non-diaphragmatic magnetic-armature as the vibratory actuating member; the receiving telephone being associated with the incoming line circuit and each microphone adjusted to exert merely a normal microphonic pressure between its contacts or electrodes; the secondary-relays being sensitive and adapted to increase and uniformly magnify currents received by them; a primary circuit, including a battery, in circuit

with the microphone of each primary-relay, said primary circuits being associated inductively with a respective secondary local circuit in which the receiver of the secondary-relay is connected, the microphones of the secondary relays being adjusted to exert merely a normal microphonic pressure between their contacts or electrodes and each microphone having a primary circuit, including a battery, associated inductively with its respective out-going line.

2. The combination in a telephone repeater, of two repeaters, each including a pair, at each repeater station each pair adapted to repeat in a direction opposite to the other, each pair comprising a compound telephone repeater composed of a receiving or primary relay and a transmitting or secondary-relay; the primary relays consisting of a sensitive receiving telephone and transmitting microphone without a diaphragm and a non-diaphragmatic magnetic armature as the vibratory actuating member, the receiving telephones being associated with the incoming line circuit, and each microphone adjusted to exert merely a normal microphonic pressure between its contacts or electrodes; the secondary-relays being sensitive and adapted to increase and uniformly magnify currents received by them; a primary circuit, including a battery, in circuit with the microphone of each primary-relay, said primary circuits being associated inductively with a respective secondary local circuit in which the receiver of the secondary relay is connected, the microphones of the secondary relays being adjusted to exert merely a normal microphonic pressure between their contacts or electrodes, and each microphone having a primary circuit including a battery associated inductively with its respective out-going line, and circuit means and associated inductive means for preventing self-action of the repeaters.

45 3. The combination in a telephone repeater of two repeaters each including a pair at each repeater station, each pair adapted to repeat in a direction opposite to the other, each pair comprising a compound telephone repeater composed of a receiving or primary-relay and a transmitting or secondary-relay; the primary relays consisting of a sensitive receiving telephone and transmitting microphone without a diaphragm and a non-diaphragmatic magnetic armature as the vibratory actuating member, the receiving telephone being associated inductively with the incoming line circuit, and each microphone adjusted to exert merely a normal microphonic pressure between its contacts or electrodes; the secondary relays being sensitive and adapted to increase and uniformly magnify currents received by them; a primary circuit, including a battery, in circuit with the microphone

of each primary relay, said primary circuits being associated inductively with a respective secondary local circuit in which the receiver of the secondary-relay is connected, the microphones of the secondary relays being adjusted to exert merely a normal microphonic pressure between their contacts or electrodes and each microphone having a primary circuit, including a battery, associated inductively with its respective out-going line and circuit means and associated inductive means for preventing self-action of the repeater.

4. In a telephone repeater, the combination of a repeater-circuit adapted to reciprocal retransmission with means therein for balancing the circuit against reaction of the repeater, a relay comprising a receiver and a transmitter in repeater relation and having as its actuating vibratory element or armature a freely oscillatory tongue or reed-like regulable vibrator for electro-mechanically associating the receiver with the transmitter, and dominating means for damping said tongue, substantially as described.

5. In a telephone repeater, the combination of a repeater-circuit adapted to reciprocal retransmission with means therein for balancing the circuit against reaction of the repeater, a relay comprising a receiver and a transmitter in repeater relation and having as its actuating vibratory element or armature a freely oscillatory tongue or reed-like regulable polarized vibrator for electro-mechanically associating the receiver with the transmitter, and dominating means for damping said tongue, substantially as described.

6. The combination in a double compound telephone repeater having reciprocating instrumentalities and functions arranged and operating in opposed order, the opposed instrumentalities each consisting in the following-apparatus, circuits and adjustments, to wit: a primary or first relay with its winding connected in circuit with the inward line, said relay having no diaphragm but having a vibratory armature non-diaphragmatic in form, the microphone of said relay having a normal adjustment, a primary circuit for said microphone, including a battery and the primary of an induction coil, a neutralizing local circuit for said first relay to prevent reaction by repeated currents; a secondary relay with its winding connected in a local secondary circuit, said local secondary circuit also including the secondary winding of the said induction coil, the microphone of the secondary relay having a normal adjustment, a primary circuit in which said secondary relay microphone is connected with a battery and the primary of the second induction coil, a secondary winding for said second induction

coil with which the outward line is in circuit, substantially as described.

7. In a compound reciprocating telephone repeater comprising two pairs of relays for stepping-up the transmission and wherein the relays forming each pair are connected together by means of a local primary and a local secondary circuit, said pairs being arranged electrically opposed for reciprocal

automatic unidirectional transmission, the combination therewith of neutralizing circuit means and neutralizing induction coil means, both means being within local circuits, for the prevention of self-action.
